(57) CLAIM

I claim the ornamental design for an air removal device, as shown and described.

DESCRIPTION

FIG. 1 is a top front perspective view of the claimed design; FIG. 2 is a right side view thereof; FIG. 3 is a left side view thereof; FIG. 4 is a front view thereof; FIG. 5 is a rear side view thereof; FIG. 6 is a top view thereof; and, FIG. 7 is a bottom view thereof.

The ornamental design which is claimed is shown in solid lines in the drawings. The broken lines in the drawings are for illustrative purposes only and form no part of the claimed design.
